UNITED STATES PATENT OFFICE.

JOHN L. DAWES, OF PITTSBURG, PENNSYLVANIA.

DESIGN FOR A BOTTLE.

SPECIFICATION forming part of Design No. 20,656, dated March 31, 1891.

Application filed March 9, 1891. Serial No. 384,351. Term of patent 7 years.

To all whom it may concern:

Be it known that I, JOHN L. DAWES, of Pittsburgh, in the county of Allegheny and State of Pennsylvania, have invented a new and original Design for Bottles, of which the following is a full, clear, and exact description, reference being had to the accompanying drawings, forming part of this specification, in which—

10 Figure 1 shows in side elevation a bottle having my design. Fig. 2 is a sectional plan thereof.

15 My invention consists in the design for bottles, substantially as shown in the drawings and as hereinafter described.

20 2 represents the body of the bottle, which is of cylindrical form, having at the base a peripheral ornamental band 3, which band projects outwardly from the bottle and is formed with a series of adjacent concavities or de-

pressions 4 of slightly oblong or elliptical outline, which extend from the bottom of the band to the top.

25 5 is a bottle-stopper, the top of which is circular and of greater diameter than the lower part. Around the margin of the top is a series of adjacent concavities 6, corresponding in appearance to the series at the base of the bottle. The presence of such series at both ends of the bottle gives it a peculiarly unique 30 and ornamental appearance.

I claim—

The design for bottles, substantially as herein shown and described.

In testimony whereof I have hereunto set 35 my hand this 27th day of February, A. D. 1891.
JOHN L. DAWES.
